UNITED STATES PATENT OFFICE.

MICHAEL W. PIASECKI, OF WEST ALLIS, WISCONSIN.

DRAFT-GEAR-REMOVING MEANS.

Application filed July 7, 1923. Serial No. 650,159.

To all whom it may concern:

Be it known that I, MICHAEL W. PIASECKI, a citizen of the United States, and a resident of West Allis, in the county of Milwaukee and State of Wisconsin, have invented certain new and useful Improvements in Draft-Gear-Removing Means, of which the following is a description, reference being had to the accompanying drawings, which form a part of my specification.

My invention relates to means whereby the draft gears of railroad cars, that is to say the spring containing pockets or yokes and contained elements, may be removed from their position between the draw-lugs or members secured between the car-sills when occasion requires for inspection and replacement of worn parts.

The invention has for its object the provision of means whereby the draft gear may be quickly removed from its position between the draw-lugs or non-movable members without causing damage or injury to the draft gear or any of the car parts associated therewith.

The objects and advantages of my invention will be more readily comprehended from the detailed description of the accompanying drawings, wherein:

Figure 1 is a partial longitudinal sectional view, with parts broken away showing a portion of the car-sills or underframe and draft gear in side elevation and my improved removing means or puller shown in operative position.

Figure 2 is a vertical sectional view taken substantially on the line 2—2 of Figure 1 looking in the direction of the arrows.

Figure 3 is a detail view in perspective of one of the yokes or members of my improved means employed at the forward end of the draft gear.

Figure 4 is a similar view of a yoke or member of my improved means employed at the rear or inner end of the draft gear, as disclosed in Figure 1.

Figure 5 is a sectional plan view of a draft gear with my improved pulling means as disclosed in Figure 1.

Figure 6 is a side elevation, with parts broken away, of a draft gear with a modified form of my improved pulling or removing means.

Figures 7 and 8 are detail perspective views showing the yokes or members em-

ployed with the construction disclosed in Figure 6.

My invention has for its object the provision of means whereby the draft gear, namely the spring containing yoke with its contained elements, may be readily pulled downward from between the draw-lugs or non-moving members secured between and to the car sills, in order that the draft gear may be properly inspected and any of the worn parts replaced. The removal of the draft gear has heretofore been accomplished in a rather make-shift manner, to-wit through the employment of planks or timbers which were inserted over the top of the draft gear while the outer ends of the planks or timbers were forced upwardly by suitable means as for example screw-jacks so as to wedge the draft gear downward from between the draw-lugs. This practice not only requires considerable labor and time, but also involves an element of danger or injury to the workman, through breakage of the planks or timbers and otherwise, as well as also causing frequent damage to the draft gear.

With my improved means the removing of the draft gear may be accomplished with materially less labor and in a comparatively short period of time, while all danger of injury both to the workman and to the draft gear or car-parts is eliminated.

In the particular exemplification of the invention as disclosed in the first five figures, a well known type of draft gear is indicated generally at 15, provided with the usual follower plates 16, mounted within what is commonly known as the yoke or spring pocket 17 and all secured between the draw-lugs or members 18; which are rigidly secured to the car-sills; the draft gear being usually supported by suitable tie-straps disposed therebeneath and bolted thereto; the tie-straps having been removed in illustrating my invention and in applying my improved means.

The removing means or puller in the exemplification comprises a pair of vertically disposed side planks or timbers 19, 19 which are secured in place by means of bolts indicated at 20, extending through the planks and inserted through the holes or slots in the flanges by the members 18 which receive the bolts whereby the tie-straps or carrier members were secured in place. Each of

the side planks 19 is provided with a pair of dogs 21, 21 pivotally secured thereto at 22 with the hook-ends of the dogs depending a predetermined distance beneath the side planks 19. The dogs 21 are adapted to swing laterally and their operative or adjusted positions are maintained by means of the pivoted walls 23 which are adapted to swing vertically, with their free ends preferably bent and arranged to be in abutting relation with the sides of the dogs 21, as shown in Figure 1.

The free bent ends of the two dogs 21, pivoted to the same side plank, are disposed toward each other and adapted to support a bearing plank 24 disposed transversely and beneath the side planks 19. The puller also includes a yoke member 25, preferably provided with reinforcing ribs as 26, see Figure 4, and having depending portions or hooks 27 spaced apart and adapted to straddle the spring pocket or yoke member 17 of the draft gear and engage with the forward face of the follower plate 16, located at the rear end of the draft gear. The lower end of the yoke member 25 is bent upwardly to provide a hook portion 28 see Figures 1 and 4, which is intended to receive a suitably shaped link member 29, preferably of the rectangular formation shown more clearly in Figure 2, and which link member is provided with the two chains or supporting elements 30 whose lower ends are secured to suitable eye-bolts 31 disposed 35 through a suitable supporting plank 32 which preferably extends the full length of the draft gear as shown in Figures 1 and 5.

The forward end of the supporting plank or timber 32 is held in place by similar eye-bolts 31 adjacent opposite sides thereof, each receiving the lower end of a chain or flexible element 30, whose upper ends are secured to a single link 29. The link 29 of the chains or element 30, at the forward end of the device, is adapted to hook onto the hook portion 33 of a yoke member 34 which is preferably of the construction more clearly shown in Figure 3. The horizontally disposed portion of the yoke member 34 is provided with an opening as at 35 adapted to receive the upper end of the tail-pin 36 of the draft gear and to be held in place by the nut 37 of the tail-pin. That is to say, the nut 37 is removed from the tail-pin and 55 the yoke member 34 put into place with the tail-pin disposed through opening 35 after which the nut 37 is screwed onto the upper end of the tail-pin, thereby firmly clamping yoke member 34 in place at the forward end 60 of the draft gear.

The various elements of my puller means are now properly secured in place to receive the action or thrust of a suitable jack, indicated generally at 38, which is placed 65 on the supporting plank or timber 32. The

length of the chains or elements 30, 30 are preferably such that the normal distance between cross-timber 24 and supporting timber 32 is just sufficient to receive the unexpanded jack 38 therebetween with the upper end engaging the transversely disposed plank or timber 24.

It is apparent that upon actuation of the jack 38 whereby it is forced into distended condition, the force exerted thereby, by reason of the fact that the upper end is in firm engagement with plank or timber 34, (which latter bears against the lower edges of planks or timbers 19 and which in turn are in rigid bearing relation with the draw-lugs 80 or side members 18 of the draft gear) will cause the force to move supporting timber or plank 32 downwardly. Such downward movement of the plank or timber 32 causes a pulling force to be exerted on the yokes 25 and 34, through the medium of the chains 30, with the result that the spring pocket or yoke of the draft gear with the contained springs and follower-plates will be pulled downwardly from between the draw-lugs or rigid members and cause the spring pocket or yoke 17 with the contained springs to fall onto the transversely disposed plank 24; while the plank or timber 32 with the jack will drop onto the ground or floor.

The yoke members 25 and 34 are preferably so formed as to extend parallel with the ends of the spring pocket or yoke 17 of the draft gear and for that reason the yoke 25 in the vertical portion thereof, at an intermediate point, is shown apertured at 39 to fit over the end of the rivet 40 in the yoke or spring pocket member 17, as shown in Figure 1 in order that the yoke or hook member 25 may lie flush with the rear end 100 of the spring pocket.

With the spring pocket or yoke 17 removed from between the draw-lugs, it is apparent that the moving elements of the draft gear will be accessible for inspection 110 and replacement of any worn parts.

In railroad practice, the draft gears are required to be carefully inspected whenever the car is sent into the shops and such inspection requires the entire removal of the draft gear, or rather the spring pocket or yoke 17 and its contained elements. The operation of removal as heretofore accomplished in a rather make-shift manner, requires considerable time and labor, coupled 115 with the danger incident thereto as well as the injury of the draft gear parts or adjacent under-structure of the car, because of the firm wedging of the spring pocket with the follower plates between the draw-lugs or rigidly held members and the pressure exerted by the springs. With my improved device, the removal of the spring pocket or yoke with its contained elements can be accomplished in a materially less period of 120 125 130

time and without danger to the workmen or possible injury to the draft gear and adjacent car parts.

In Figures 6, 7 and 8, I show a modification of my invention. In this construction the timbers or planks 19 and 24 are similar in construction and arrangement to that previously shown and described and similarly secured in place; the plank or timber 24 being supported in place, transversely of the lower edge of the timber 19, by the pivoted dogs 21, which latter are locked in operative position by means of the pawls 23. In this construction, however, I employ a heavy metallic plate 41 which is intended to be placed lengthwise on top of the spring pocket or yoke 17 after the tail-pin has been removed from the draft gear. The metallic plate 41 at its ends is formed to pass through apertures in the upper ends of a pair of hooks or yoke members 42 and 43 arranged, respectively, at the rear and forward ends of the draft gear. The hook or yoke member 42, shown in detail in Figure 8, has an upper forwardly bent end 44 and a rectangular opening 45, adjacent to the upper end, to receive the end of the metallic plate 41; the hook or yoke member 42, at a suitable point, also having an aperture, as at 46, adapted to register with the rivet 40 in the yoke member or spring pocket 17, so as to permit the hook or yoke member 42 to lie flush with the rear end of the spring pocket 17. The lower end of the member 42 is bent outwardly into hook form, as at 47, to receive the link 29 whereby chains 30 and the jack supporting plank or timber 32 (not shown in Figure 6) are held in place. The hook or yoke member 43 shown in detail in Figure 7 is shown provided with a rectangular opening as at 48, adjacent to the upper laterally disposed end, to receive the end of the metallic plate 41; while the lower end is bent upwardly and outwardly to provide the hook portion 49 adapted to receive the link 29 of the pair of chains 30 whereby the forward end of the jack supporting plank or timber 32 (not shown in Figure 6) is secured in place.

In practice, the tie-straps of the draft gear are first removed; the side planks or members 19, 19 are then secured in place by passing the upper ends of the bolts thereof through the openings or slots for the tie-strap bolts; plank or timber 24 may then be secured in place by proper movement of the dogs and pawls 21 and 23. The small yoke or hook members 25 and 34 may then be secured in place by having the lugs 27, 27 of member 25 engage the forward side of follower-plate 16, while member 34 is secured in place by the tail-pin 36; or with the construction shown in Figure 6, the plate 41 is placed over the yoke 17 and the

members 42 and 43 inserted onto the ends of the plate 41. The jack supporting plank 32, with a suitable jack, is then put into place by slipping the links 29 onto the hook-ends of members 25 and 34, or 42 and 43, as the case may be. The various elements are now in position to operate the jack so as to distend it until sufficient downward pressure on timber or plank 32 has been exerted to cause yoke 17 with the springs and follower plates to drop down.

I have shown and described what I believe are the simplest and best embodiments of my invention and have described the same in terms employed merely as terms of description and not as terms of limitation, as structural modifications are possible and may be made without, however, departing from the spirit of my invention.

What I claim is:—

1. Means of the character described, comprising a plurality of thrust receiving members, a portion of said members being adapted to be suspended from the immovable portions of a car draft-gear, while the other portion of said members is adapted to be suspended from the spring-pocket or yoke member of the draft-gear, and expansible pressure exerting means disposed intermediate of both portions of said members, whereby the last mentioned portion with the spring pocket or yoke of the draft-gear will be forced downwardly.

2. Means of the character described, comprising a plurality of thrust receiving members, one portion whereof is adapted to be immovably suspended from the draw-lugs of a draft-gear, while the other portion is adapted to be suspended from the spring pocket or yoke of the draft-gear, and expansible power exerting means disposed intermediate of both portions so as to exert pressure on the second mentioned portion and thereby pull the spring-pocket or yoke of the draft gear downwardly.

3. Means of the character described, comprising a plurality of non-flexing members, one portion whereof is adapted to be rigidly secured beneath a car-underframe while the other portion is adapted to be suspended from the movable parts of the draft-gear, and means adapted to be disposed between both portions so as to exert downward pressure on the second mentioned portion and thereby pull the movable parts of the draft-gear downwardly.

4. Means of the character described, comprising a plurality of non-flexing members, a portion whereof is adapted to be immovably secured beneath the draw-lugs of a car draft-gear and on opposite sides thereof, a second portion of said members being adapted to be suspended beneath the first portion and disposed lengthwise of the draft gear, means whereby the second por-

tion may be removably secured to the spring-pocket or yoke of the draft-gear, and an expansible jack disposed between both portions of said members in pressure exerting relation therewith, whereby distention of the jack will force the second portion of members downwardly and thereby pull the spring-pocket or yoke from between the draw-lugs of the draft-gear.

10 5. Means of the character described, comprising a pair of non-flexing members adapted to be immovably secured beneath the draw-lugs of a car draft-gear, a third non-flexing member adapted to be secured to the lower edges of said first mentioned members, transversely of the draft-gear, a fourth non-flexing member adapted to be disposed beneath the third member, lengthwise of the movable portion of the draft-gear, means whereby the fourth member may be suspended from the upper surface of the movable portion of the draft-gear, and an expansible jack mounted on the fourth member in bearing relation with the third member, whereby distention of the jack will cause the fourth member with the movable portion of the draft-gear to move downwardly.

6. Means of the character described, comprising a pair of non-flexing vertically disposed members adapted to be immovably secured on opposite sides of the movable portion of a car draft-gear, a third non-flexing horizontally disposed member adapted to extend in a direction transversely of the draft gear, means whereby said third member is removably secured to said pair of members, a fourth non-flexing member adapted to be disposed in a direction lengthwise of the draft-gear and beneath the third

member, means adapted to engage with the upper surface of the spring-pocket or yoke of the draft-gear and at opposite ends thereof, for suspending the fourth member in place, and distensible pressure exerting means arranged on the fourth member in pressing relation with the third member, whereby distention of said means will cause the fourth member through said second mentioned means to pull the spring-pocket or yoke from between the draw-lugs of the draft-gear.

7. In means of the character described, a vertically disposed plank secured in bearing relation with the lower edge of each draw-lug of a draft-gear, a third plank arranged transversely of the lower edges of the vertically disposed planks, means pivotally secured to the vertically disposed planks for removably holding the third plank in abutting relation with the vertically disposed planks, a fourth plank disposed lengthwise of the draft-gear, in spaced relation beneath the third plank, yoke members adapted to be secured at the front and rear ends of the spring-pocket or yoke of the draft-gear, means whereby the fourth plank may be suspended from said yoke members, and a distensible jack disposed between the third and fourth planks in bearing relation therewith, whereby distention of the jack causes the fourth plank, through said second mentioned means and the yoke members, to pull the spring-pocket or yoke from between the draw-lugs of the draft-gear.

MICHAEL W. PIASECKI.
